UNITED STATES PATENT OFFICE.

EUGENE BRETNAY AND HARRY R. BRETNAY, OF INDIANAPOLIS, INDIANA.

MECHANICAL STOKER.

SPECIFICATION forming part of Letters Patent No. 755,611, dated March 29, 1904.

Application filed October 19, 1903. Serial No. 177,578. (No model.)

To all whom it may concern:

Be it known that we, EUGENE BRETNAY and HARRY R. BRETNAY, citizens of the United States, residing at Indianapolis, in the county of Marion and State of Indiana, have invented certain new and useful Improvements in Mechanical Stokers, of which the following is a specification.

The object of our present invention is to produce a simple, efficient, durable, and inexpensive mechanical stoker for automatically feeding fuel to furnaces whereby the fuel may be coked at its initial entrance to the fire-bed or conducted from its initial to any desired point in the furnace for such coking and whereby such fuel may be reduced to an incandescent state near its initial entrance or at such distance therefrom as may be desired and by a suitably-controlled air-blast may at will be caused to produce a higher degree of combustion at different points of the fire-bed as may be desired, and which will carry the ashes, clinkers, &c., from the fire-bed without permitting them to escape therethrough and deliver them to a suitable receptacle for convenient removal, obviating the necessity of ash-pits as commonly employed, all as will be hereinafter more particularly described and claimed.

The accompanying drawings illustrate our invention.

Figure 1 is a view of a furnace construction, showing our apparatus partially in section and partially in side elevation, a feeding-hopper being shown in connection therewith.

Fig. 2 is a plan of the top and conveyor on a somewhat-enlarged scale. Fig. 3 is a cross-sectional view on the dotted line 3-3 in Fig. 2.

Fig. 4 is a fragmentary detail illustrating more plainly our valve or damper arrangement.

In the drawings, 10 indicates a suitable hopper for conveying fuel to the furnace. As shown, said hopper at its rear has a sliding wall 11, operated to be raised and lowered by a lever structure 12 to regulate the amount of fuel to be fed to the furnace. We provide therein a valve 13, slidably operated to control the fuel-discharge for the lower chamber of said hopper. In said hopper we also provide a door 14, which may be slidably adjust-

able or suitably hinged and latched to the hopper-frame, which door is for the purpose of access to or inspection of the furnace and which, as will be understood, is usable when the fuel-supply is cut off from the upper chamber by the valve 13.

In the combustion-chamber we provide a receptacle 20, of desired design and dimensions, having aprons 21 and 22 extending from its upper ends, and secured upon said receptacle or box is a perforated cover or top 23. Upon the under side of said perforated top 23 we provide a plurality of slideable perforated plates or valves 24 of sufficient number to underlie the perforated top entirely or only a limited number, as may be desired, but which former arrangement we have illustrated and prefer. These valves, as shown, are adapted to be shifted transversely of the perforated top and the perforations therein caused to register with the perforations in the top or the imperforate portions thereof caused to obstruct said perforations in the top, said valve-plates being shown as controlled by suitable handles 25, projecting from the sides of the top plate 23 out through the fire-wall, whereby the valves may be manipulated singly at will, although we do not desire to be understood as limiting ourselves to such manipulating means, as under some circumstances the valves may be connected in pairs or greater numbers, so that more than one may be shifted at one operation, or a shifting thereof may be accomplished by other than the means shown and differently than transversely of the top plate.

Within the receptacle 20 we introduce a blast-pipe 26, adapted to discharge a blast through said receptacle, the blast escaping up through the perforated top 23.

At the ends of the receptacle 20 below the aprons we provide driving-shafts 27, (driven from any suitable source of power,) bearing sprocket or other suitable driving wheels 28, which drive the drag-conveyer surrounding the receptacle structure 20, said drag-conveyer being composed of suitable chains 29 and bars 30, as shown.

In the operation of our apparatus the fuel is delivered through a hopper or other suitable means to the point *a*, from whence it is

conveyed by the drag-conveyer lengthwise of the perforated top at any desired degree of speed. At the point *a* over the apron 22 the fuel, as coal, becomes coked, and as said coked fuel is conveyed across the perforated plate the blast from discharger 26 escaping through the perforations in said plate or top 23 furnishes the necessary air-supply to the coked fuel to produce perfect combustion, resulting in the reduction of the fuel to an intense incandescent or bright fire, thoroughly consuming all the combustible elements of the fuel, so that a minimum of smoke escapes therefrom. As the fuel is conducted across the top or plate by the drag-conveyer the ashes and incombustible products of the fuel are conveyed over the apron 21, falling to the base of the furnace, from whence it is conveyed by the conveyer along said base 31 to the outlet 32, where it falls into any suitable receptacle provided therefor.

By the construction of conveyer described we are not only enabled to automatically feed fuel to any portion of the fire-surface of the furnace in a very simple manner; but, as will be readily understood by the arrangement of drag-conveyer employed, we are by simply revolving the conveyer enabled to thoroughly clean the fire-bed when desired and remove the ashes, &c., over the rear portion thereof, carrying them beneath the conveyer structure over the base-plate out to near the front end of the furnace in the manner shown, or, as will also be apparent, we may reverse the movement of the conveyer, dumping the material out through the door 14. The blast escaping through the perforated plate 23 prevents ashes or other debris from falling therethrough, the same being conveyed along over the apron to the base of the furnace, as just described. By providing the dampers or valves 24 the escape of blast through the perforated top 23 may be controlled, so that by opening all of the valve-plates to register with the perforated top plate the blast may escape through the entire surface of the top, or, for instance, when we desire to convey the fuel, say, as far as *b*, to coke the valves to this point will be closed, or in cases where we do not desire that the blast escape through the entire top plate for purposes of slow combustion we may open the valves alternately or at the extreme end or in the middle or any other part, thus providing a suitable means for discharging the air-blast at any desired point and controlling

the location of fast or slow combustion of the fuel at will.

We claim as our invention—

1. In a furnace, a fuel-burning support embodying a box-like receptacle and a perforated top therefor, a blast-creating means within said receptacle adapted to discharge an air-blast longitudinally therethrough, and an endless drag-conveyer traveling about said receptacle structure, substantially as shown and described. 65

2. A receptacle for receiving an air-blast, a perforated top to said receptacle, aprons at the ends of said receptacle, driving mechanism positioned at both ends of said receptacle beneath said aprons, and an endless drag-conveyer surrounding said described structure and driven by said driving mechanism, as shown and described. 70

3. The combination, in a furnace, of a receptacle embodying a perforated fuel-supporting top, a blast-discharger leading into said receptacle, aprons at the respective ends of said receptacle, driving mechanism positioned beneath said aprons, a drag-conveyer surrounding said described structure operated by said driving mechanism, valves in said perforated top, and means for operating said valves, substantially as shown and described. 75 80

4. In an apparatus of the class described, a blast-receptacle embodying a fuel-supporting top, a drag-conveyer composed of chains and bars as shown and described traversing the upper and lower surface of said receptacle, and means for driving said conveyer, substantially as and for the purposes set forth. 85 90

5. In a furnace, a blast-receptacle embodying aprons at either end, a perforated fuel-supporting top covering said receptacle, valves connected with said top, driving mechanism at either end of said receptacle beneath said aprons, a drag-conveyer composed of chains and bars surrounding said described structure, a base as 31, and a discharge-outlet as 32, all substantially as shown and described and for 100 the purpose set forth.

In witness whereof we have hereunto set our hands and seals, at Indianapolis, Indiana, this 12th day of October, A. D. 1903.
